(57) CLAIM

The ornamental design for a shoe sole, as shown and described.

DESCRIPTION

FIG. 1 is a bottom perspective view of a first embodiment of a shoe sole, in accordance with my new design;
FIG. 2 is a rear perspective view of the first embodiment;
FIG. 3 is a bottom view of the first embodiment;

FIG. 4 is a right side view of the first embodiment;
FIG. 5 is a left side view of the first embodiment;
FIG. 6 is a rear view of the first embodiment;
FIG. 7 is a front view of the first embodiment;

FIG. 8 is a bottom perspective view of a second embodiment of a shoe sole, in accordance with my new design;
FIG. 9 is a rear perspective view of the second embodiment;
FIG. 10 is a bottom view of the second embodiment;

FIG. 11 is a right side view of the second embodiment;
FIG. 12 is a left side view of the second embodiment;
FIG. 13 is a rear view of the second embodiment;

FIG. 14 is a front view of the second embodiment; and,
FIG. 15 is a top view of the first and of the second embodiments.

The broken lines shown depict environmental subject matter and are included for the purpose of illustrating the unclaimed portions of the shoe that form no part of the claimed design.

1 Claim, 15 Drawing Sheets
